UNITED STATES PATENT OFFICE.

THOMAS HIPWELL, OF ASTORIA, ASSIGNOR TO THE MANHATTAN BRASS COMPANY, OF NEW YORK, N. Y.

LAMP-BURNER.

SPECIFICATION forming part of Letters Patent No. 314,178, dated March 17, 1885.

Application filed March 17, 1884. (No model.)

To all whom it may concern:

Be it known that I, THOMAS HIPWELL, of Astoria, in the county of Queens and State of New York, have invented an Improvement in 5 Lamp-Burners, of which the following is a specification.

Lamps and lanterns have been made with a movable section in the air-distributer, or in the metal plate below the burner, to be moved 10 aside to admit a match or lighter. These, however, require to be closed by hand after the lamp is lighted.

My invention relates to the combination, with a section in the air-distributer, of a hinge 15 and a spring, which spring becomes a lever for moving the section in opening and closing the space through which the lighter is inserted.

In the drawings, Figure 1 is a plan with the 20 air-distributer section depressed. Fig. 2 is a vertical section. Fig. 3 is the movable section and spring separately. Fig. 4 is a detached view of the hinge-plate, and Fig. 5 is a plan view of the movable section alone. The 25 parts in Figs. 3 and 4 are shown in enlarged size.

The wick-tube *a*, base *b*, ratchet-cap *c*, arms *d*, air-distributer *e*, deflector or cone *f*, and chimney-springs *g* are of ordinary character, 30 shape, and arrangement, except that the air-distributer, instead of being in one piece, is cut out so as to have an opening at one side of the wick-tube. The piece that is separated forms a movable section, *e'*. In this section 35 *e'*, I cut a slot or mortise at *i*, and around the wick-tube I place a hinge-plate, *l*, that is by preference soldered to the under side of the

air-distributer; and I provide a tongue, *u*, that is passed through the mortise in the section *e'* and turned over, so as to form a hinge upon 40 which the section can be swung up or down.

The spring *o* is riveted to the under side of the section *e'*, and forms a lever-handle for the same, by which to move said section. The spring is bent double, so that its free end rests 45 upon the ratchet-cap at the junction thereof with the wick-tube. This holds the section *e'* up level with the other portion of the air-distributer; but when the spring is moved so as to open the burner for lighting the wick the 50 free end of the spring slides up upon the side of the wick-tube. When the lever-spring is liberated, it resumes its normal position and raises the air-distributer section.

I claim as my invention—

55

1. The air-distributer section having a slot near its edge, in combination with the hinge-piece surrounding the wick-tube, and having a tongue to pass through the slot and form a hinge, and a lever or handle to open or close 60 the section, substantially as set forth.

2. The combination, in a lamp-burner, of an air-distributer with an opening in it, a section to fit such opening, a hinge upon which the section can be swung, and a lever-spring fastened at one end to the section, and the other end resting upon the ratchet-cap or wick-tube, 65 substantially as set forth.

Signed by me this 7th day of March, A. D. 1884.

THOMAS HIPWELL.
